UNITED STATES PATENT OFFICE.

PATRICK H. DURACK, OF EL PASO, TEXAS

MEANS FOR VENTILATING AND EXPELLING WATER FROM MINES.

No. 893,988.

Specification of Letters Patent.

Patented July 21, 1908

Application filed October 16, 1907. Serial No. 397,620.

To all whom it may concern:

Be it known that I, PATRICK H. DURACK, a citizen of the United States, and a resident of El Paso, in the county of El Paso and State 5 of Texas, have invented certain new and useful Improvements in Means for Ventilating and Expelling Water from Mines, of which the following is a specification.

There are many rich and valuable mines of 10 gold, silver and lead ores, which cannot be worked because of the accumulated water, which cannot be pumped out and the efforts to remove which cost the owners many thousands of dollars and frequently without success. In the ordinary method of removing 15 water by pumps, the pumps are more or less in the way of the men when working sinking the shaft, and a break down in the pumping machinery, which is always liable to occur, is 20 a serious disaster, as the water drives the men out, the work has to be shut down, and the pumps down in the mine are submerged beneath from one hundred to two hundred feet of water. The result is that the mine 25 has to be abandoned after thousands of dollars have been spent in trying to keep it dry.

My invention is designed to be applied to 30 mines of the above named character and also to coal mines, heavy tunnels, and in fact all underground work where large bodies of 35 water are encountered, and its purpose is to ventilate the mines with fresh air, drive out all the foul air, dust and gases, keep the mine clear of explosive or dangerous substances 40 which might collect in the same from time to time, and maintain the mine dry and clear of water.

To these ends my invention provides a system 45 of ventilation and of expulsion of water by means of a circulating body of fresh air, and air locks so arranged as to permit the work to be progressively carried on without interruption, allowing the mine to be developed and worked with greater safety than 50 with the appliances heretofore employed, eliminating the danger of explosion from the foul air, gases or dust, and affording protection to the miner both by day and night while the work is carried on continuously 55 without the delays incident to blasting, etc.

In the drawing Figure 1 is a vertical section taken through a mine provided with my improved air locks and system of ventilating pipes, valves, etc., and Fig. 2 is a vertical section on an enlarged scale taken through the upper air lock at the surface showing the

means for discharging the air or coal raised in the cage or car for delivery to the exterior of the air lock.

Referring to Fig. 1, A is a sheet metal 60 caisson placed in the mouth of the shaft, and B is the upper air lock placed on top of the caisson and bolted to the same. The air lock B is a perfectly tight sheet metal casing fitted to the caisson A with air tight joints 65 which are carefully closed by white lead cement. The caisson A is cemented all around outside in the mouth of the shaft so as to form a closed air chamber capable of containing the requisite air pressure in the 70 mine. Beside the air lock B and communicating with it through an opening b' is a subsidiary air chamber B' through which egress and ingress from the mine is obtained. The subsidiary air chamber B' is capable of being 75 thrown into open communication with the chamber B through the opening b' or to have communication therewith cut off by a ~~solid~~ 80 door D having air tight joints about the edges of the opening b'. The subsidiary chamber B' also has an external door D' through which the miners may enter or emerge and this door is in like manner formed with air tight joints for a purpose to be hereafter described. An inlet valve a 85 arranged between the chambers B and B' is provided for the purpose of introducing the air pressure within the air lock B into the chamber B' for equalizing the pressure between the two and said subsidiary chamber 90 B' is also provided with an outlet valve b through which, when the door D is closed, the air pressure within the chamber B' may be discharged into the open air to establish 95 equilibrium between the air within the subsidiary chamber B' and the outer air. The purpose of this arrangement is to enable the miners to be gradually adjusted to the air pressure within the mine in entering the same and to be gradually adjusted to the 100 atmospheric air in leaving the mine, and without material loss of air pressure from within the chamber B. For this purpose in entering the mine the door D is tightly closed, and the door D' is opened, the miners 105 entering the chamber B' and closing the door D' behind them. They then open the valve a which allows the pressure within the chamber B to gradually enter the subsidiary chamber B'. After equilibrium is restored 110 between the chambers B and B' the door D is opened and the miners then pass into the

air pressure of the chamber B and the door D being then closed they descend into the mine. In leaving the mine the door D' of the subsidiary chamber being closed, the door D is opened and the miners from the cage enter the subsidiary chamber B' and close the door D behind them. The valve a being now closed and the valve b being opened, the air pressure within the chamber 10 B' escapes gradually through the valve b until the chamber B' assumes the same conditions of atmospheric pressure as the outside air and the miners may then open the door D' and pass out.

15 In the top of the air lock B is arranged a stuffing-box c through which passes the hoisting cable F which is attached to and lifts the cage, which cable passes over a pulley C in the frame work above the air lock and 20 is wound upon a suitable drum C' operated by an engine outside of the mine.

For the ventilation of the mine, two systems of pipes are employed. The pipe I with suitable valves i is extended to near 25 the bottom of the mine and also horizontally along the drifts or tunnels to the various headings. This pipe I receives compressed air from a cooling chamber E' outside the mine into which the air is forced from the 30 compressor operated by the engine E. The outlet pipe O extends also in a co-extensive way throughout the mine in the vertical shaft and horizontal drifts to the various headings and its purpose is to receive the 35 foul air, explosion gases and water and raise and convey them to the exterior of the mine. These pipes O with their branches O' are provided with suitable valves o, o' at the various levels to control the flow through the 40 said outlet pipe. Both the inlet air pipe I and outlet pipe O extend up to the upper air lock B and emerge from the same through the tightly closed walls.

At the bottom of the mine and also at the 45 various headings of the horizontal drifts are arranged secondary locks in the form of bulk-heads consisting of a door frame L' arranged transversely in the shaft and locked in place by suitable timbers embed- 50 ded in the side walls of the same in connection with a door L hinged at one edge to the door frame L' and fitting in a rabbet or recess therein with an air tight joint and provided with ropes and pulleys L² by means of 55 which said door may be raised and opened. In each of these doors is an escape valve y.

Whenever all the secondary locks or bulk-heads L, L' are closed, it will be seen that the 60 fresh air entering through the inlet pipes I, I' is delivered into the heading beyond the bulk-heads and the foul air and gases are forcibly driven out through the outlet pipes O, O', and discharged outside of the mine.

At the bottom of the shaft at the lower end 65 of the outlet pipe O, a flexible hose h with a

large strainer at the bottom of the same is provided which extends down to the lowest level and is employed for taking the water from the levels under superincumbent pressure of air and driving it out through the 70 pipe O so as to relieve the mine of accumulated water by the action of the pneumatic pressure.

In blasting I have shown, on the left-hand side of the horizontal tunnel, a bulk-head 75 door L, as closed, and the blast which takes place in the heading beyond this bulk head does not in any way interfere with the 80 workings at the other headings or at the bottom of the mine since its gases are confined and by a proper manipulation of the valves in the inlet and outlet pipes, foul air and gases within the heading are forced out by the incoming fresh air until all of such gases are removed.

The secondary lock or bulk-head L, L' at the bottom of the mine not only permits the above described operation to take place and the water to be automatically removed as fast as it accumulates, but it also extends 90 across the mine shaft above the miner at the bottom of the mine and thereby affords protection against the accidental falling of the rocks, etc. so that he may continuously perform his work. It will also be seen that my 95 system of ventilation permits the miners at each one of the headings to perform their work continuously and independently of the operation of blasting in other tunnels without in any way being inconvenienced there 100 by or having their air contaminated by the gases of the blasting.

When the men are ready to blast the bulk head door is closed, the valve in the discharge pipe is opened allowing the air to pass out 105 between the heading and the secondary air lock L, the feed valve being shut. After blasting the air is again turned in and drives the foul air and gases through the outlet pipe O. The discharge valve o is then shut, the 110 bulk head door L or L' of the subsidiary lock is open and the men can at once return to their work. In the meantime the blasting does not disturb or in any way affect the men working in any other part of the mine. All 115 the pipes are to run about ten feet past the bulk-heads and must be in position to receive all foul air and to deliver fresh cold air to the men after blasting. As the work at the headings progresses the bulk-head locks 120 L, L' are to be moved from time to time to a closer position to the heading, the bulk-head lock being kept at about twenty-five feet from the heading in order that the men need not have too far to go when blasting. Moreover, by having this lock as close as possible to the heading the amount of air lost when 125 blasting is reduced to a minimum.

The general pressure throughout the whole mine is maintained at a sufficient point to 130

keep the water back out of the mine and for this purpose an automatic relief valve R is employed to allow the air to blow off at any excessive pressure.

5 With my invention I am able to handle any kind of mine and it makes but little difference how much water there is in it as it can be forced out and kept out for one-half the cost of the pumping. If there is more than one main shaft, then in that case, if the shaft is to be worked I place an external lock B above the mouth of the same, which is operated in the same way, or if the second shaft be vacant and it connects with the mine, then one of the bulk-head subsidiary air locks L, L' is placed in it with a blow off valve in it so as to have a good circulation of air.

When working mines with my invention 20 the air can also be used for working air drills. Electricity may also be employed to light the mine as the pressure will not affect it since it will not ordinarily be more than fifteen pounds to the square inch. Should it be desired to 25 work the mine in the old way, that is, to do the blasting at night and morning, in this case, all that is required is the lock B B' since all the drilling may be done in the day time and the blasting afterwards. In this way the 30 pipes are all run down to the bottom of the shaft and the bulk-head is used in the bottom of the shaft simply because of the protection which it affords the miners should they want to do any blasting through the 35 day or between times without causing delay to the balance of the work.

All the inlet air pipes in the mines are furnished with foot valves to prevent any back 40 action that might occur to the air compressor. Referring to Fig. 2, I will describe how the ore, etc. raised by means of the cable F is discharged from the upper air lock. This air lock is provided on one side with a sliding door B² which opens communication into 45 two hoppers G and H. The hopper G is provided with a sliding door G' having rack teeth engaging a gear wheel G² on a shaft, by turning which the door G' may be raised to open the outlet of the hopper G or be lowered 50 to seal this hopper air tight. The lower hopper H is also provided on the bottom side with an air tight hinged door H' which when closed cuts off the air lock B from the external air. If the ore is raised in the ordinary 55 way by direct lift of the cable F, it is discharged into the lower hopper H, but if the ore is raised by means of the skip car and inclined railway as shown in dotted lines, the ore is discharged into the upper hopper G. If

60 discharged into the lower hopper H, the door H' is maintained closed and the door B² is opened. After the ore has been discharged into the hopper H the door B² is closed and the door H' opened to discharge the ore from 65 said hopper without material loss of air from

the air lock B. If the ore is discharged into the upper hopper G the door G' is maintained closed or in its lowest position and the door B² is raised to its highest position. The ore is then discharged into the hopper G. The door B² is then lowered and closed and the door G' then raised to discharge the ore from said upper hopper which also prevents the escape of air from the upper air lock B.

I claim—

1. Means for ventilating and expelling water from mines, comprising an upper air lock at the mouth of the mine provided with a subsidiary entrance chamber, one or more secondary air locks arranged transversely in the mine shafts, an inlet pipe extending throughout the shafts and tunnels of the mine and provided with valves, an outlet pipe co-extensive with the inlet air pipe and provided with valves, both of said pipes being extended past the secondary air locks and into the headings.

2. Means for ventilating and expelling water from mines, comprising an upper air lock at the mouth of the mine with means for ingress and egress, one or more secondary air locks arranged transversely in the mine shafts, an inlet pipe extending throughout the shafts and tunnels of the mine and provided with valves, an outlet pipe co-extensive with the inlet air pipe and provided with valves, both of said pipes being extended past the secondary air locks and into the headings, and a flexible hose attached to the outlet pipe and having a strainer on its end and extending down to the water level of the mine.

3. Means for ventilating and expelling water from mines, comprising an upper air lock at the mouth of the mine with means for ingress and egress, one or more secondary air locks arranged transversely in the mine shafts, an inlet pipe extending throughout the shafts and tunnels of the mine and provided with valves, an outlet pipe co-extensive with the inlet air pipe and provided with valves, both of said pipes being extended past the secondary air locks and into the headings, the air lock at the mouth of the mine being provided with a subsidiary entrance chamber and doors, and two valves one opening communication between the main air lock chamber and the subsidiary chamber, and the other opening communication between the subsidiary air chamber and the outer air.

4. Means for ventilating and expelling water from mines, comprising an upper air lock at the mouth of the mine with means for ingress and egress, one or more secondary air locks arranged transversely in the mine shafts, an inlet pipe extending throughout the shafts and tunnels of the mine and provided with valves, an outlet pipe co-extensive with the inlet air pipe and provided with

valves, both of said pipes being extended past the secondary air locks and into the headings, the air lock at the mouth of the mine being formed with a hopper closed on all sides and provided with two doors, one being arranged between the hopper and the air lock and the other between the hopper and the outside air.

5. In a means for ventilating and expelling water from mines, the combination with a system of air inlet and discharge pipes ex-

tending through the mine and provided with valves, of an external air lock arranged at the mouth of the mine and having said pipes extending through the side walls thereof, a 15 stuffing box arranged in the top of said air lock and a hoisting cable passing through said stuffing box.
